(57) **CLAIM**

The ornamental design for an “electric musical instrument,” as shown and described.

DESCRIPTION

FIG. 1 is a front elevation view of an electric musical instrument, showing my new design;

FIG. 2 is a back elevation view of thereof;

FIG. 3 is a left side elevation view of thereof;

FIG. 4 is a right side elevation view of thereof;

FIG. 5 is an enlarged top plan view of thereof;

FIG. 6 is an enlarged bottom plan view of thereof;

FIG. 7 is an enlarged front and left side lower perspective view thereof;

FIG. 8 is an enlarged front and left side upper perspective view thereof;

FIG. 9 is an enlarged front view of the upper portion of FIG. 1;

FIG. 10 is an enlarged back view thereof;

FIG. 11 is an enlarged right side view thereof, the left side view being a mirror image;

FIG. 12 is an enlarged front view of the lower portion of FIG. 1;

FIG. 13 is an enlarged back view thereof;

FIG. 14 is an enlarged right side elevation view thereof, the left side view being a mirror image; and,

FIG. 15 is an enlarged portion of the right side thereof, the left side being a mirror image.

The break lines have been applied in FIGS. 7-15 for ease of illustration and form no part of the claimed design.

1 Claim, 7 Drawing Sheets
